DESIGN FOR A PEN DESK STAND

Frank N. Mariani, New York, N. Y.

Application August 13, 1936, Serial No. 64,402

Term of patent 7 years

To all whom it may concern:

Be it known that I, Frank N. Mariani, a citizen of the United States, residing in Manhattan, in the city, county, and State of New York, have invented a new, original, and ornamental Design for Pen Desk Stands, of which the following is a specification, reference being had to the accompanying drawing, forming a part thereof in which:—

Fig. 1 is a plan view of my pen desk stand according to the invention.

Fig. 2 is a side elevational view thereof and Fig. 3 is a front view of Fig. 2.

The dominant features of my design reside in the combination annular and funnel pen support shown in full lines.

I claim:—

The ornamental design for a pen desk stand, substantially as shown and described.

FRANK N. MARIANI.
